COMPANY, OF NEW BERLIN, OHIO, A CORPORATION OF OHIO.

SUCTION CARPET-SWEeper.

1,151,731.

Specification of Letters Patent. Patented Aug. 31, 1915.

Application filed November 29, 1912. Serial No. 733,988.

REISSUED

To all whom it may concern:

Be it known that I, JAMES M. SPANGLER, a citizen of the United States, residing at Canton, in the county of Stark and State 5 of Ohio, have invented a new and useful Suction Carpet-Sweeper, of which the following is a specification.

This invention relates to improvements in carpet sweepers provided with means for 10 producing a suction or strong inrush of air into the device, which inrush of air operates in conjunction with the brush for the purpose of brushing and pneumatically cleaning floors and floor coverings and similar 15 surfaces.

The objects of this invention are to generally improve devices of the character mentioned, and to provide a construction which will be composed of few and simple 20 parts put together in a practical, mechanical manner, the various parts being so exactly and peculiarly adapted to each other that they combine to produce a very superior, substantial and efficient carpet sweeper.

One of the important objects of the invention is to provide a brush and brush adjustment in combination with a driving wheel and sweeper supporting adjustment 25 for the purpose of regulating and adjusting 30 the sweeper in accordance with the class of work which it is intended to do and to accommodate the natural wear of the brush.

These objects, together with other objects apparent to those skilled in the art may be 35 attained by the construction illustrated in the accompanying drawings, although the invention may be embodied in other forms, the construction illustrated being chosen by way of example.

In the drawings Figure 1 is a perspective 40 view of a suction carpet sweeper embodying my invention. Fig. 2 is an inside perspective view of one of the driving wheels removed from its bearing. Fig. 3 is an outside end, fragmentary elevation of one of the front corners of the device. Fig. 4 is a similar view showing the driving wheel removed. Fig. 5 is a sectional view taken on the line 5—5 of Fig. 3. Fig. 6 is a view 45 similar to Fig. 3, but with both driving wheel, wheel plate and brush hanger removed. Fig. 7 is an inner side elevation of one of the wheel plates and the brush hanger connected thereto. Fig. 8 is a perspective view of one of the brush hangers.

Fig. 9 is a perspective view of the wheel plate. Fig. 10 is a perspective view of the lubricating packing and wheel retaining screw and washer. Fig. 11 is a sectional view through the brush casing on the line 11—11 of Fig. 6. Fig. 12 is a longitudinal sectional view through the brush.

Throughout the several views similar reference numerals indicate similar parts.

More specifically describing the construction illustrated in said drawings, the numeral 1 indicates the main casing of the carpet sweeper within which is mounted a fan, 1^a such as is well known to those skilled in the art and which is adapted to exhaust 60 the air from said casing into the dust bag 2, which is connected to the outlet 3 of the casing and serves as a receptacle for the dirt and dust lifted by the device. Said fan is preferably driven by an electric motor 4 mounted upon the casing, the flexible conductor 5 leading through the switch 6 serving to transmit the current from any suitable source to the motor. The handle 7 is pivotally connected to the casing 1 by 65 means of the yoke 8 and is employed for manually moving the sweeper over the floor or surface to be cleaned.

The forward portion of the casing 1 is provided with a brush casing 9 which extends transversely and is arranged at a somewhat lower level than the main portion of the casing 1. The interior of said casing 9 is substantially cylindrical, but the side of said casing adjacent the floor is somewhat squared off on a plane parallel with the floor, as shown in Fig. 6, and a slot-like brush and intake opening 10 extending parallel with the axis of cylindricity of the casing 9 is arranged upon the lower side of 70 said casing 9, as is common in carpet sweepers of this general character.

It should be noted that it is important in sweepers of the class to which this invention belongs, to have the brush or sweeping 75 means operate in an effective manner so as to free the dust and dirt from the floor or floor coverings, permit the inrush of air to accomplish its work more thoroughly and to assist said inrush of air in picking up particles which have a tendency to adhere to the surface being cleaned. The motor and fan portion of the device having been properly constructed and adjusted by the manufacturer require little or no attention 80

through years of use and are substantially permanently adjusted for all classes and kinds of work to which the sweeper may be adapted, but in the art of suction cleaning it is a well known fact that it is important to adjust the intake opening with relation to the plane of the surface being cleaned as an adjustment of said opening too far removed from said surface permits an inrush of air without lifting the dirt and dust, whereas too close adjustment of said opening to said surface reduces the volume of air permitted to enter and draws said opening down, frequently impeding the free movement of the sweeper over the floor, thus not only lessening the effectiveness of the device, but also increasing the difficulty of its management.

It will also be understood that the brushes in sweepers of this character must be properly adjusted with reference to the brush or intake opening so as to effectively contact with the surface being cleaned, while at the same time having proper adjustment with relation to the intake opening in order that the best results may be accomplished. Not only is this true with reference to any one surface upon which the device is used, but such adjustment may be intelligently varied to suit conditions, for the sweeper commonly employed in a home having mostly hardwood or other uncovered floors and few and relatively thin rugs should be somewhat differently adjusted from a similar sweeper in use in a home having no bare floors and heavy, thick carpets. It should also be noted that, unlike the motor and fan, the brush is necessarily subjected to appreciable wear and means whereby said brush may be adjusted to compensate for such wear is essential. It will be apparent, therefore, that in a sweeper of the character concerned it is necessary that the traveling wheels or supporting means for the casing provided with the intake opening be adjustable with reference to said casing and that the brush mounted within said casing may also be adjustable with reference to said casing, and that said brush and traveling wheels or other supporting means be also adjustable with reference to each other.

Further considering the drawings it will be noted that in Fig. 6 the inner surface of the casing 9 is indicated by the dotted line 11 and the outer periphery of the bristles 12 of the brush is indicated by the dotted circle 13. The end of the casing is provided with a slight, inwardly turned, annular flange 14 which in Fig. 6 is shown as extending across the intake opening, forming a light bridge or tie at 15. In the flange 14 are arranged screw threaded apertures 16 and 17 for the purpose hereinafter more fully to appear.

The construction of the brush is quite fully illustrated in Figs. 11 and 12 where

it will be noted that the same is made in two parts or members 18 and 19 arranged end to end and rotatably mounted upon a stationary brush shaft 20. Each of the brush members is provided with a longitudinal bore of greater diameter than the shaft 20 and an oil-impregnated fibrous bushing 21 is fixedly mounted within the bore at the inner end of each brush member, which bushings constitute the bearings of said members upon the shaft 20. In this manner a freely running, non-heating bearing is provided which does not require attention to keep it lubricated and in good condition. The inner end of the member 18 is provided with an outstanding annular rib 22 which covers the joint where the two members abut, producing a construction wherein it may be said that the inner end of the member 19 rotates within a recess in the inner end of the member 18, as clearly shown in Fig. 12. The outer surface of the rib 22 being rounded, acts as a thread guard and prevents threads and the like from being wound into the space or joint between the members 18 and 19. When a thread is picked up by the bristles of the brush and begins to wind upon the brush members the rib 22 will guide it entirely over on to one or other of the members, thus effectually guarding the brush against the trouble of thread-binding. The extreme outer ends of the members 18 and 19 are provided with the integral disk portions 23 on the inner side of which the depressed annular groove 24 is arranged for the purpose of acting as a thread guard to prevent threads being wound about the members 18 and 19 at the ends and thus thread-binding the same. A pinion 25 is fixedly connected to the outer end of each brush member or is formed integrally therewith as may be preferred and is adapted to rotate about the shaft 20 with the member to which it is connected.

At each end of the casing 9 is provided a wheel plate, one of which is shown in Fig. 9. Said wheel plate consists of a forward, casing closing portion 26 and a rear, driving wheel backing portion 27, said portions 26 and 27 being formed integrally and preferably in the same plane. In the midst of the portion 26 is a brush hanger aperture 28 which is in the form of a vertically disposed slot permitting vertical adjustment of the brush with reference to the wheel plate as hereinafter described.

Adjacent the lower front edge of the portion 26 is an aperture 29, and in the upper portion of the plate is the aperture 30, said apertures being substantially diametrically opposite each other, considering the circular form of the casing 9, and each of said apertures 29 and 30 being in the form of a slot extending in the direction of the curvature of the casing 9. Machine screws 31 and 32

- extend through the apertures 29 and 30 respectively and into the apertures 16 and 17 for the purpose of clamping the wheel plate to the end of the casing 9, the slotted character 5 of the apertures 29 and 30 permitting some rotary adjustment of the wheel plate about the axis of curvature of said casing 9 and the said screws being adapted to clamp the plate to the flange 14 in any desired adjustment.
- 10 For the purpose of holding the wheel plate in proper position with reference to the axis of curvature of the casing 9 the inner side of the wheel plate is provided with integral curved ribs 33 which engage the inner edge 15 of the flange 14, as clearly illustrated in Fig. 11.

On the outer side of the wheel plate substantially at the center of the portion 27 is arranged the outstanding wheel stud 34 for 20 the attachment of the driving wheel. At its free end said stud is provided with a recess 35, from which recess an oil conducting aperture 36 leads to the outer bearing surface of the stud. From the bottom of said recess 35 a screw threaded aperture 37 leads entirely through the wheel plate.

On the inner side of each wheel plate is arranged a brush hanger, one of said hangers being illustrated in Fig. 8. It will be 30 noted that said hanger is provided with a connecting arm 38 and an adjusting head 39 and intermediate said head and said arm an outward extending pinion housing 40 is provided. Said housing 40 is adapted to extend through the aperture 28 of the wheel plate to which the hanger is attached and said housing is cut away at the side adjacent the arm 38. An end wall 41 forms an integral portion of said housing 40 and an aperture 42 in said wall 41 is adapted to receive 40 the end of the shaft 20. Said aperture 42 may be round or elongated, at least one of the ends of the shaft 20 being correspondingly elongated or shaped to prevent rotation of the shaft 20. A screw 43 extending through the aperture 44 in the end of the arm 38 and into the screw threaded aperture 37 pivotally connects the brush hanger to the wheel plate, the axis of said pivotal 50 connection being co-incident with the axis of the stud 34. In the forward part of the portion 26 of the wheel plate is a slot 45 of curved form through which the screw 46 extends from the outer side of the wheel plate 55 into the screw threaded aperture 47 in the head 39. The screw 46 being adjustable within the slot 45 permits the brush hanger to be pivotally moved upon the screw 43 as a center so as to move the pinion housing 40 up and down within the aperture 28, and said screw 46 may be drawn down firmly to hold the brush hanger in any desired adjustment within the limits of the slot 45.

From an inspection of Fig. 11 it will be noted that the pinions 25 extend into the

housing 40 and the sides of the housing 40 adjacent the arms 38 being cut away said pinions are partially exposed upon the outer side of the wheel plate, as clearly shown in Fig. 4.

70 The driving wheels are each of the form particularly illustrated in Figs. 2 and 5. It will be noted that said wheels comprise an outer disk portion 48 provided with a peripheral inturned flange 49 upon which is 75 suitably mounted a rubber or other friction tire 50. On the inner side of the disk portion 48 is fixedly mounted a pinion 51. Extending centrally through said pinion 51 and disk 48 is a bearing aperture 52 adapted to rotatably receive the stud 34. On the outer side of the disk 48 is a circular recess at 53 concentric with the aperture 52 and a retaining washer 54 is adapted to be rotatably arranged within said recess. A felt 80 or other lubricating holding packing 55 is adapted to be arranged within the recess 53 in the wheel stud and has a central aperture 56 through which the retaining screw 57 extends, as well as through the washer 54, said screw 57 being adapted to fit the screw threaded aperture 37, as illustrated in Fig. 5. The stud 34 is of sufficient length to permit the driving wheel to freely rotate thereon when connected thereto as described, and 90 the pinion 51 is adapted to mesh with the pinion 25.

95 It will be apparent that by reason of the construction just described each brush member will be geared to one of the driving 100 wheels and will be free to rotate in accordance with the direction of rotation of said driving wheel.

To move the casing 9 toward or from the surface to be cleaned it is only necessary to 105 slightly loosen the screws 31 and 32 and rotate the wheel plates about the axis of curvature of the casing 9, the ribs 33 retaining the plates in proper position regardless of their regular adjustment. In this way the 110 driving wheels may be raised or lowered with reference to the casing for the purpose of adjusting the intake slot with reference to the surface to be cleaned. Such adjustment of the driving wheels, however, does 115 not necessarily alter the adjustment of the brush. To adjust the brush with reference with the wheel plate it is only necessary to loosen the screws 46 and swing the brush hangers upon their pivoting screws 43, 120 whereupon said screws 46 may be drawn up to hold the brush in its new adjustment. It is thus possible to adjust the brush and traveling wheels with relation to each other and to adjust either brush or wheels with 125 relation to the casing 9.

Attention should be called to the packing 55 which when thoroughly saturated with oil feeds a proper quantity of the same through the oil aperture 36 to the external 130

surface of the wheel stud and thus properly lubricates the driving wheel bearing.

I claim:

1. A suction carpet sweeper comprising an elongated rotatable brush, a brush casing therefor having on its underside a cleaning intake opening, said casing at the ends provided with end walls having circular end openings adapted to permit endwise removal of said brush therethrough, wheel plates connected to the ends of said brush casing on the outer sides of said end walls and having inwardly disposed ribs engaging the curved edges of said end openings and adapted to permit rotary adjustment of said plates while maintaining said plates and end openings in concentric position, and traveling wheels rotatably connected to said wheel plates upon axes eccentric with reference to the common axis of said plates and openings.
2. A suction carpet sweeper comprising a casing provided with a cleaning intake opening, wheel plates adjustably connected to said casing, traveling wheels rotatably mounted upon said wheel plates, and a rotatable brush arranged within said casing and adjustably connected to said wheel plates.
3. A suction carpet sweeper comprising a casing provided with a cleaning intake opening, wheel plates connected to said casing and adapted for rotary adjustment with relation to said casing, traveling wheels rotatably connected to said wheel plates upon an axis eccentric with reference to the axis of said rotary adjustment, a rotatable brush arranged in said casing at said intake opening, brush hanging means pivotally connected to said wheel plates in the axis of said traveling wheels, said brush connected to said brush hanging means eccentrically with reference to the axis of said pivotal connection, and means for operatively connecting said wheels to said brush.
4. A suction carpet sweeper comprising an elongated rotatable brush, a casing therefor provided on its underside with a cleaning intake opening, said casing open at the ends and provided at each end with an inwardly disposed, integral, complete, circular flange defining a circular opening adapted to permit endwise removal of said brush therethrough, wheel plates on the outer sides of said flanges, closing said circular openings, and provided on their inner sides with portions engaging the edges of said openings to permit rotary adjustment of said plates about centers common with the centers of said openings, traveling wheels rotatably mounted on the outer sides of said wheel plates upon axes eccentric with reference to said centers, and said brush, having its ends extended through said wheel plates and operatively connected to said traveling wheels.

In testimony that I claim the above, I have hereunto subscribed my name in the presence of two witnesses.

JAMES M. SPANGLER.
